UNITED STATES PATENT OFFICE.

JAMES T. COWLEY, OF NEW YORK, N. Y., ASSIGNOR TO THE LAMSON STORE SERVICE COMPANY, OF BOSTON, MASSACHUSETTS.

STORE-SERVICE APPARATUS.

SPECIFICATION forming part of Letters Patent No. 394,835, dated December 18, 1888.

Application filed May 6, 1887. Serial No. 237,347. (No model.)

To all whom it may concern:

Be it known that I, JAMES T. COWLEY, a citizen of the United States, residing in the city, county, and State of New York, have invented certain new and useful Improvements 5 in Store-Service Apparatus, of which the following is a specification.

My invention relates to that class of store-service apparatus in which it is desired to arrest or deflect certain carriers at certain points upon the way or track; and my invention consists in providing each carrier with a movable contact-piece adapted to arrest or deflect the carrier by contact with a device adjacent to 10 the way, and in setting or altering the position of the contact-piece upon the carrier by the movement of one of the wheels of the carrier after the latter has traversed a predetermined distance.

20 My invention further consists in a means for holding in their open position the yielding gates sometimes employed upon certain classes of carriers.

In the accompanying drawings, Figure 1 is 25 a side elevation of a store-service carrier embodying my invention. Fig. 2 is an elevation in part section showing the parts in a different position. Fig. 3 is a sectional elevation taken on the line *v v* of Fig. 1. Fig. 4 is a 30 central sectional elevation of a sleeve, disk, and worm-wheel, hereinafter described. Fig. 5 is a transverse section illustrating a modification. Fig. 6 is a side view illustrating a modification.

35 The carrier may be of any suitable construction, and the track A may consist of a single wire or bar, or of parallel rails either inclined or horizontal or capable of being altered in inclination for the purpose of propelling the carrier by gravity, as my invention 40 is adapted to be used in connection with various constructions of carriers and systems of store-service. As shown, the carrier is provided with a frame, B, supported from the 45 way by means of two grooved wheels, C C', and one of the wheels is provided with a shaft carrying a worm-gear, 2, which gears with a worm-wheel, 3, upon the shaft 4, carried by the frame and having a central worm, 5. The 50 frame B also carries a slide, D, capable of a vertical movement and provided with a suit-

able detent—as, for instance, a detent-lever, E, having a shoulder, 6, which engages with a shoulder, 7, on the frame, and thereby maintains the slide D in its most elevated position. 55 A spring, 62, is provided on the slide to bear against the detent-lever E and hold it in engagement with the shoulder 7, and also cause it to automatically engage therewith when the slide is raised to its normal position. Obviously this detent-lever might be weighted to effect the same result as said spring. The slide D also carries a hub or sleeve, 8, upon which is mounted a disk, 9, and also a worm-wheel, 10, the latter adapted to engage with 60 the worm 5 when the slide is in the elevated position, (shown in Fig. 1,) and the disk 9 is provided with a projection, 12, which, when brought against one side of the detent-lever E, will swing it in the direction of the arrow, Fig. 2, and carry the shoulder 6 away from the shoulder 7 and near the slide, and the parts carried thereby will fall either by its weight or by its weight aided by a spring, 61, to the position shown in Fig. 2. This 65 movement of the slide is made the means of varying the position of the movable contact-piece or lever F, pivoted to the frame at 60, and also connected to the slide by a pin, 61, which lever, when in the position 70 shown in Fig. 1, produces no effect—that is to say, the lever is in such position with respect to the means which is to arrest or deflect a carrier that it passes said means without arresting or deflecting its carrier; but when carried to the position shown in Fig. 2, by the 75 dropping of the slide, the lever is then in position to make contact with a contact-piece, G, that serves to deflect the carrier and cause it to pass either to another track or arrests its 80 motion upon the main track or disconnects it from the main track in any of the various 85 manners in which carriers have been deflected, arrested, and disconnected in store-service apparatus, and which need not be here 90 specifically set forth. In the construction shown the end of the lever F is curved, so that when it contacts with the piece G it deflects the carrier to one side and causes it to 95 pass onto a branch track.

In order that the carrier may be deflected to the proper point, it is necessary to drop the 100

slide before the carrier arrives at the contact-piece G, which is to operate it. I therefore provide means for adjusting the projection 12, carried by the disk 9. For instance, the 5 disk may have a series of perforations, x, into which a pin, 62, (see Fig. 4,) extending from the projection 12, may be set in any suitable position, so that the projection may contact with the detent-lever E after the car has 10 moved to a determined extent.

In practical operation the wheels C C' are revolved as the car moves upon the wire, and the revolution of the wheel C, through the intermediate parts, turns the disk 9 until the 15 lug or projection 12 thereon contacts with the detent-lever E, when the latter will be thrown back and disengaged from its shoulder 7, when the slide will drop and the lever F will be set in position to operate in connection with the 20 contact-piece G. When the slide D drops, as in Fig. 2, the disk 9 and worm-wheel 10 are carried with it, and these parts may then be restored automatically to their initial position before being raised to their normal position, 25 as in Fig. 1, by a spring, 13, connected to a stud or pin, 14, that supports the hub or sleeve 8, carrying the disk and worm-wheel 10, and also connected to the said hub or sleeve or to the disk, so as to be coiled up as the disk 30 is turned by the revolution of the shaft 4 in the direction of the arrow, Fig. 1, and when the slide D drops and the worm-wheel 10 is removed from gear with the worm 5 and the disk is free to turn the spring 13 will reverse 35 its movement until a stop, 15, upon the disk is brought in contact with the detent-lever E and ready to be raised to the normal position. The spring 91, for aiding the descent of the slide and the disengagement of the worm and 40 wheel 10, is held at the lower end of the frame and is borne against by a stud projecting from the side of the slide. Before the car is sent back, which is done generally after it is removed from the way, the outer end of the lever F is depressed, should the automatic arresting or deflecting of the carrier be necessary on its return to its place of starting, when 45 the parts will be raised and restored to their first position, (shown in Fig. 1,) and the car 50 will travel until the detent-lever is again moved back by contact with the lug, pin, or projection 12, when the operations above described are repeated.

I have shown the appliances which I have 55 just described and which are illustrated in the drawings simply for the purpose of illustrating my invention as embodied in one form of construction; but I have devised various means of adjusting a lever or other contact-piece upon the car from the revolution of the wheels, so that after the car has traveled the determined distance the said lever or contact-piece will be in position to engage with another contact piece or device upon or adjacent to the way, which will cause the arrest of the car at its proper station or deflect it at the proper point onto a branch track. I there-

fore do not limit myself to the particular construction shown. For the purpose of illustrating another arrangement embodying the 70 same principle, I have shown in Fig. 5 the frame B as suspended from wheels C, one of which turns upon a pin, 16, and has its hub formed into or carries a worm-wheel, 42, that engages upon a worm, 43, on a shaft, 44, carried by brackets 17 of the frame and carrying a contact piece or arm, F', which is changed in position as the car moves along the track A until it is in a horizontal position (shown in dotted lines) or otherwise in position to 80 make contact with any suitable device for arresting or deflecting the car.

In Fig. 6 the shaft of one of the wheels is provided with a small pinion, 18, which gears with a rack, 19, upon an arm, 20, pivoted to 85 the frame and carrying a contact-piece, F², which, when the arm has been raised to the proper extent, will bring the piece F² in position to contact with the proper device for arresting or deflecting the car. The rack 19 is shown as pivoted to the arm 20 and pressed outward by a spring, 53, which insures the engagement of the rack and pinion, but permits the rack to be thrown back to adjust the arm.

Other modes of adjusting a contact-piece upon the car by the movement derived from one of the wheels will suggest themselves to any one familiar with the art. I prefer, however, such an arrangement as will avoid the 100 setting of the contact-piece until just prior to the time when it should strike the device which is to arrest or deflect the car, so that at other times the said contact-piece will be out of the way of other arresting devices with 105 which other cars passing upon the same way may have to contact.

In that class of store-service apparatus where it is desired to lock the carrier to the way by means of pivoted wings or guards H 110 H, as shown in Fig. 1, the said guards are maintained generally in elevated positions until depressed upon passing the supports of the way by means of a connecting-spring, 29.

An objection to the arrangements heretofore adopted has been that the guards are always under the influence of the spring tending to elevate it, so as to interfere with the quick placing of the carrier upon the way. To avoid this I connect each end of the spring 115 to a stud or bearing, 21, upon the wing, so arranged that when the wing is at its upper position the bearing 21 will be above the pivot 22 of the wing; but when the wing is turned down to its lowest position the bearings 21 will 120 be below said pivots, so that the spring then will act to draw the guards together and hold them in their lowest position. The spring thus holds the guards in both their highest and lowest positions, according as they are 125 set, and of course when moved to their lowest position in passing a track-support they may be returned to their highest position automatically by any suitable means—such as the 130

cam 24 (dotted lines, Fig. 1)—on or near the track, which will contact with the guard-studs 25 in a manner well known, which studs may be sleeved, so that they may roll when 5 contacting with the cam, as 24, in operating the guards.

Without limiting myself to the precise construction and arrangement of parts shown, I claim—

- 10 1. The combination, with a car for store-service apparatus, of a movable stop-contacting piece, as F, carried by the car, and connections between the said piece and one of the wheels, whereby the rotation of the latter as 15 the car travels upon the way is made the means of adjusting the said contacting-piece into operative position, substantially as set forth.
2. The combination, in a car for store-service apparatus, of a frame supported by the wheels of the car, a stop-contacting piece, as F, adjustable upon said frame, and connections between the said contact-piece and one of the wheels, whereby it is moved into operative 25 position from the movement of said wheel, substantially as set forth.

3. The combination, in a store-service apparatus, of a way, devices arranged adjacent to the way to arrest or deflect the carriers, and carriers moving upon the way provided with movable contact-pieces, as F, and operating-gears between the latter and one of the wheels, said pieces adapted to contact with the said devices, substantially as set forth.

35 4. The combination, in a carrier for a store-service apparatus, of a movable contact-piece, as F, a detent for holding the latter in one position, and a movable lug or projection geared to be operated by one of the wheels 40 and arranged to contact with the detent to release the said contact-piece and change its position after the car has traveled a predetermined distance, substantially as set forth.

5. The combination of a car, a contact-piece 45 consisting of a pivoted lever, a slide connected with said lever, a detent for maintaining the slide in its elevated position, and a sleeve or shaft carrying a lug for contacting with said detent and geared to be operated by one of the wheels, substantially as and for the purpose set forth.

6. The combination of a wheeled carrier, a contact-piece consisting of a pivoted lever, a slide connected with said lever, a detent for 55 maintaining the slide in its elevated position, a sleeve or shaft carrying a lug for contacting with said detent and geared to be operated by one of the wheels, and a spring for aiding in lowering said slide when the detent 60 is struck, substantially as described.

7. The combination of the contact-piece, as F, revolving shaft geared to be operated by one of the wheels, an adjustable lug carried by or with said shaft, and a detent in position 65 to be struck by said lug for retaining the contact-piece in position until so struck, substantially as set forth.

8. The combination, in a wheeled carrier, of the contacting-piece, as F, a slide, a revolvable lug carried by said slide and geared to be 70 operated by one of the wheels, and a detent also carried by said slide in position to be struck by said lug, whereby to adjust the position of the contact-piece, substantially as described.

9. The combination, in a wheeled carrier, 75 of a contact-piece, as F, a revolvable shaft geared to be operated by one of the wheels and carrying a lug, and a detent for holding the shaft in gear and in position to be contacted by said lug to remove said shaft from 80 gear with said wheel, substantially as described.

10. The combination, in a wheeled carrier, of the contact-piece, as F, revolving shaft geared to be operated by one of the wheels, 85 an adjustable lug carried with said shaft, a detent in position to be struck by said lug for retaining the contact-piece in position until so struck, and a spring for returning the lug to its initial position, substantially as 90 described.

11. The combination, in a wheeled carrier, of the contact-piece, as F, a revolving shaft geared to be operated by one of the wheels, 95 an adjustable lug carried with said shaft, a detent in position to be struck by said lug for retaining the contact-piece in position until so struck, a spring for returning the lug to its initial position, and a stop for limiting said return movement, substantially as 100 described.

12. The combination, with the wheel of a carrier and a shaft in gear therewith, of a second shaft in gear with the first-mentioned shaft and carrying a lug revolvable therewith, 105 a detent for holding said shafts in gear and in position to be struck by the lug to disengage the shafts, and a contact-piece, as F, adapted to be adjusted to operative position when the shafts are disengaged, substantially 110 as described.

13. The combination, with a wheel of a carrier and a shaft in gear therewith, of a second shaft in gear with the first-mentioned shaft and carrying a lug and adjustably 115 mounted thereon, whereby its position with respect to the detent may be changed, a detent for holding said shafts in gear and in position to be struck by the lug to disengage the shafts, and a contact-piece, as F, adapted to 120 be adjusted to operative position when the shafts are disengaged, substantially as described.

14. The combination, with a wheeled carrier, a shaft in gear therewith and provided 125 with a worm, of a second shaft having a wheel in gear with said worm and carrying a revolvable lug, a detent for holding said worm and wheel in gear and in position to be struck by the lug to disengage the worm and wheel, and 130 a contact-piece, as F, moved into operative position by the disengagement of the worm and wheel, substantially as described.

15. The combination, with a wheeled car-

- rier and a shaft in gear therewith, of a vertically-movable slide carrying a second shaft held in gear with the first-mentioned shaft by a detent, a lug carried by said second shaft 5 for contacting with said detent to disengage the shafts, and a contact-piece, as F, connected with said slide, so as to be moved into operative position when the shafts are disengaged, substantially as described.
- 10 16. The combination, with the pivoted gates of a store-service carrier, of a connecting-spring attached to said gates at bearings 21,

which are above the pivots of the gates when the latter are raised and below said pivots when the gates are lowered, substantially as 15 described.

In testimony whereof I have signed my name to this specification in the presence of two subscribing witnesses.

JAMES T. COWLEY.
